UNITED STATES PATENT OFFICE.

JAY G. ROBINSON, OF CHICAGO, ILLINOIS.

FIRE DOOR FOR FURNACES.

Application filed April 1, 1921. Serial No. 457,761.

To all whom it may concern:

Be it known that I, JAY G. ROBINSON, a citizen of the United States, residing at Chicago, in the county of Cook and State 5 of Illinois, have invented certain new and useful Improvements in Fire Doors for Furnaces; and I do hereby declare the following to be a full, clear, and exact description of the invention, such as will enable 10 others skilled in the art to which it appertains to make and use the same.

The invention relates to locomotive boilers, furnaces and other similar structures, and more particularly to mechanically 15 operated doors adapted to cover the fire box opening in the above named structures.

The principal object of my invention, broadly stated, is to provide means, in connection with fluid pressure operated doors, 20 for releasing the fluid pressure when the doors are in closed position to permit the manual opening thereof and to provide lever mechanism to facilitate this manual operation.

Another object of the invention is to provide means in connection with fluid pressure operated doors, wherein the doors are normally moved to closed position by fluid pressure, for releasing the doors from fluid pressure, 25 sure to permit them to be placed in any desired open position, the arrangement being such that the doors are automatically retained in open position for any desired period of time.

There are other objects of the invention as will hereinafter more fully appear in connection with the detailed description of the preferred embodiment thereof which has been illustrated in the accompanying drawings, 30 the novel features being pointed out in the claims at the end of the specification.

In the drawings,—

Figure 1 is a view in front elevation of a locomotive fire door mechanism embodying 40 the invention.

Figure 2 is a view in side elevation of the structure shown in Fig. 1.

Figure 3 is a detail view, partially in plan and partially in section, showing the 50 mechanism for manually controlling the doors and illustrating the latter in partially opened or cracked position; and

Figure 4 is a fragmentary sectional view showing the interior of the fluid pressure cylinder and illustrating one of the elements 55 of the invention.

Throughout the specification and drawings like parts are designated by like reference characters.

The numeral 1 designates a door ring 60 which is intended to be fitted to the opening of the fire box in any desired manner, preferably by means of fastening devices which are adapted to extend through the slots 2 in the ears 3 with which the ring 1 65 is provided. The door ring is formed with an opening 4, indicated by dotted lines, corresponding in size to the opening in the fire box, and the opening 4 is adapted to be closed by a pair of vertically movable doors 70 5 and 6. In the particular embodiment of the invention illustrated in the drawings the doors 5 and 6 are pivoted, respectively, on pivots 7 and 8 which are preferably located adjacent the corresponding ends of the doors 75 5 and 6, the door 5 being adapted to move upwardly and the lower door 6 downwardly to open position, as will be clearly understood from the drawings. On the opposite side of the door ring 1 from the pivots 7 80 and 8 is provided a keeper 9 which overlies portions of the doors 5 and 6 when the latter are in closed or partly open position. The said keeper is adapted to prevent an explosion in the fire box from forcing the 85 doors away from the door ring and breaking the doors intermediate their ends.

Extending across and in front of the doors at their pivoted ends is a cover plate 10 which is fully described in my co-pending 90 application Serial No. 425,850, filed November 22, 1920, and need not be further described herein except to state that this cover plate, in connection with the door ring, forms the bearings for the outer ends of 95 the pivoted members 7 and 8 and also serves to support the fluid pressure operating cylinder 11 and the lever mechanism 12 herein-after more fully described by which the fluid pressure mechanism serves to open and 100 close the doors 5 and 6.

Within the cylinder 11 I provide a plurality of spaced pistons 13 and 14, the piston 13 being larger in diameter than the piston 14. The piston rod 15 extends downwardly 105 through the lower end of the cylinder and is pivotally connected to a lever 16 which in turn is pivotally connected at its opposite ends to levers 17 and 18, respectively, the lever 17 being pivotally connected intermediate its ends to the door ring 1 by means 110 of the pivoted member 19 and being con-

5 nected adjacent its outer end to the door 5 by means of a link 20 which is pivotally connected to both the lever 17 and to the door 5. The lever 18 is connected at one 5 end to the door ring by means of the pivotal member 21 and is pivotally connected adjacent its opposite end to the door 6 by means of a link 22.

10 Fluid pressure connections 23 and 24, respectively, are adapted to be controlled by a valve 25 which is movable by means of a pivoted foot lever 26. When the foot lever 26 is pressed downwardly the valve member 25 is moved upwardly, thereby 15 opening the pipe 23 so as to permit the fluid pressure from the source of supply to enter between the top of the cylinder 11 and the upper end of the piston 13. The space between the pistons 13 and 14 is always connected with the source of supply of fluid pressure by means of the pipe 24 and the passage 27 to which said pipe is connected. When the pressure is introduced between the piston 13 and the top of the cylinder it 25 will be apparent that the combined downward pressures on pistons 13 and 14 will be greater than the upward pressure on piston 13 and consequently this excess of downward pressure will force the pistons 13 and 30 14 downwardly in the cylinder, opening the doors 5 and 6. As the piston 13 moves downwardly the fluid which is between the pistons 13 and 14 will be reduced in volume owing to the difference in the diameters of 35 the respective portions of the cylinder in which the said pistons operate. This decrease in volume results in increasing the pressure between the pistons, since a check valve of any ordinary construction is provided in the passage 24. The check valve while freely admitting fluid pressure through the passage 27 automatically prevents the flow of fluid in the opposite direction when the pressure in the cylinder exceeds the pressure in the source of fluid supply. Consequently as the piston 13 45 approaches the lower end of its respective portion of the cylinder 11, the pressure against the lower face of the piston increases until at a point adjacent the lower end of its stroke this pressure exactly counterbalances the pressure against the upper face of the piston 13. This method of operation results in the doors being brought to 50 full open position and provides an air cushion which prevents any jar or destructive action upon the parts of the operating mechanism. When the foot lever 26 is released the operation is reversed, that is, the valve controlling the admission of fluid pressure between the upper end of the cylinder and the top of the piston 13 is closed and an exhaust port is opened permitting the escape of this fluid pressure. The pressure upon the lower face of the piston 13,

no longer being counterbalanced by the pressure upon the upper face thereof, will move the piston 13 upwardly and bring the doors to closed position. Preferably there is an exhaust port leading from the upper portion of the cylinder 11 which is adapted to be closed or blinded by the piston 13 adjacent the end of its upward stroke, thus trapping a small volume of air between the piston 13 and the top of the cylinder. This entrapped air acts as a cushion to prevent the slamming of the doors with consequent damage to the latter and to their attachments and holds the doors in slightly spaced relation. There is, however, provided a bleed port (not shown) leading from this portion of the cylinder which slowly permits the escape of this entrapped air, thus permitting the upward pressure on the piston 13 to bring the doors into tightly closed position. The construction hereinabove described is shown and fully described in my co-pending application, Serial No. 4358, filed Jan. 25, 1915, and the descriptive matter is only inserted herein in order to accurately describe the operation of the construction shown. It will be observed that a downward movement of the piston rod 15 will force the lever 16 downwardly, and, owing to the connection of the lever 16 with the levers 17 and 18, will cause the doors to be moved to open position, and likewise upward movement of the lever 16 will result in a closing movement of the doors 5 and 6. Inasmuch as the pressure from the source 100 of supply is always admitted between the pistons 13 and 14 (except as hereinafter described) it will be obvious that the doors 5 and 6 will be held in closed position by a locking pressure which is measured by the 105 difference in diameter or area of the pistons 13 and 14.

The passageway which leads from the source of fluid supply to the space between the pistons 13 and 14 is clearly illustrated 110 in Fig. 4 and designated by the reference numeral 27. At a convenient point in this passage I provide a cylindrical opening 28 in which is seated a three-way stop cock 29. In normal position the passage 30 in 115 the three-way stop cock or valve is in alignment with the corresponding ends of the passage 27 and permits the entrance of the fluid pressure to the space between the pistons 13 and 14. When, however, the three-way valve is given a quarter rotation in a clockwise direction the passage 27 is intercepted by a portion of the three-way valve and the passage 31 of the three-way valve 120 is in alignment with the portion of the passage 27 leading to the cylinder 11, while the lower portion of the passage 30 is in alignment with a passage 32 which leads to the atmosphere. It will therefore be obvious 125 that when the valve 29 is turned as 130

described the compressed fluid between the pistons 13 and 14 will be released and further entrance of fluid between these pistons will be prevented until the cock 29 is again 5 rotated to its normal position.

Referring now to Fig. 3, it will be observed that I provide on the door 5 adjacent the pivot 7 thereof a bracket or lug 33. This bracket preferably comprises a 10 substantially rectangular pocket within which is connected a lever 34. Preferably the lever 34 is pivotally connected with the bracket or lug 33 by means of a pin 35 which is adapted to extend through an opening 36 15 in the said lever. In normal position of the parts illustrated in Figs. 1 and 2, it will be observed that the upper end of the lever 34 is overweighted so as to cause the same to lie of its own weight against a lug 1^x of the 20 door ring 1. To permit the lever to be maintained in this position irrespective of the opening of the doors by fluid pressure, I cut away the upper portion of the wall 37, as shown at 38, so as to permit the necessary 25 clearance between the wall and the lever to prevent the overweighted upper end of the lever from being forced away from the lug of the door ring during the fluid pressure operation of the doors. It will be noted 30 that the lever 34 is provided with an inclined portion 39 which extends over the point of pivotal connection, that is, 35, of the lever, and is further provided with a handle 40 which in normal position also overhangs 35 the pivotal point of the lever and the contacting portion of the door ring 1, and that by constructing the lever in this manner it will always lie against the door ring when the doors are operated by fluid pressure. 40

The operation of the device is believed to be clear from the foregoing description. It might be pointed out, however, that when it is desired to partially open or crack the furnace doors it is only necessary to turn the 45 valve 29 in a clockwise direction so as to release the fluid pressure between the pistons 13 and 14. The lever 34 is then operated or pulled to the left until the desired opening between the fire doors is attained; the 50 lever may then be released and if desired pushed over to a position in contact with the door ring 1. It will be obvious, however, that should the lever not have been turned to a position in contact with the door ring 55 or lug after a cracking operation of the fire doors, the closing movement of the doors will automatically return the lever to its normal position. Owing to the balance between the doors 5 and 6 it will be seen that 60 the doors will remain in any position to which the same have been moved by the lever 34 until it is the desire of the operator to close the same. To perform this closing operation the only step necessary is to give 65 the stop cock or valve 29 a quarter rotation

in a counter clockwise direction so as to bring the passage 30 thereof into alignment with the adjacent ends of the passage 27, whereupon the fluid pressure will be admitted to the space between the pistons 13 and 14, and owing to the difference in the respective diameters of these pistons the pressure will force the piston 13 upwardly, causing the doors 5 and 6 to be moved to closed position. 70

Attention is directed to the fact that by the use of the mechanism described the fireman of a locomotive is enabled to move the doors of the fire box to open position and to close the same without moving from his seat at the left hand side of the cab. The principal purpose of providing cracking mechanism for locomotive fire doors is to cool down the boiler by permitting cold air to enter above the fire, thus reducing the steam pressure within the boiler. This step is generally employed when the locomotive or train is approaching terminals when the amount of steam required for the train operation is greatly reduced. It is at this time, however, that is, when the train is approaching terminals, that the attention of the fireman is required to observe signals and to confirm the engineer in the reading of the signals controlling the approach of the train. 80 85 It is therefore imperative that the fireman be permitted to operate the cracking mechanism without moving from his seat and without having his attention distracted from his more important duty. By using the mechanism hereinbefore described it is possible for the fireman to positively control the opening of the fire doors without moving from his position and for him to maintain the doors in any desired position without 90 interposing between the doors or any portion thereof a locking mechanism. 100

Having now described my invention, what I claim and desire to secure by Letters Patent is:—

1. In a device of the character described, the combination with movable door members, of fluid pressure operated means for opening and closing the same, said means being adapted to hold said door members in 110 closed position, means for releasing said holding means and manually operated means for moving said door members to open position.

2. In a device of the character described, the combination with oppositely movable door members, of fluid pressure operated means for moving said door members to open and closed positions, said means being adapted to exert a predetermined pressure 120 upon said door members when in closed position, means for releasing said pressure and means for manually opening said doors when the said pressure is released.

3. In a device of the character described,

- the combination with radially movable door members, of means operated by fluid pressure and including a cylinder for moving said doors to open and closed positions, said 5 means being adapted to exert pressure upon said doors to lock the same in closed position, means carried by said cylinder for releasing the said locking pressure and manually operated lever means for moving said 10 door members to an open position when said locking pressure is released.
4. In a device of the character described, the combination with arcuately movable door members, of means for moving the 15 same to open and closed positions, said means including a cylinder and a plurality of spaced connected pistons, fluid pressure means for operating said pistons, said cylinder having a passage to permit the fluid 20 pressure to enter the space between said pistons when said door members are in closed position, and means located in said passage for closing the same and for venting the space between said pistons to permit the 25 manual operation of said door members.
5. In a device of the character described, the combination with arcuately movable door members, of means operated by fluid pressure and including a cylinder for normally moving said doors to open and closed positions, the said means being adapted to exert pressure upon said doors to lock the 30 same in closed position, a valve carried by said cylinder for releasing the said locking 35 pressure and manually operated lever means carried by one of said door members for moving said door members to an open position when said locking pressure is released.
6. In a device of the character described, 40 the combination with oppositely movable door members, of fluid pressure operated means for normally moving said door members to open and closed positions, said means being adapted to exert pressure against the 45 opening movement of said doors when the latter are in closed position, a three-way valve adapted to be rotated to release said pressure, and a lever pivotally connected to one of said door members for facilitating 50 the manual operation thereof to open position.
7. In a device of the character described, 55 the combination with oppositely movable door members, of means for positively moving said door members to open and closed positions, said means including a cylinder and a plurality of spaced connected pistons, fluid pressure means for operating said pistons, said cylinder having a passage to permit the fluid pressure to enter the space between said pistons, and rotatable means located in said passage for controlling the admission of fluid pressure to said cylinder intermediate the said pistons, said means being adapted in one position to vent the space 60 between the said pistons.
- In testimony whereof I affix my signature.

JAY G. ROBINSON.
